(57) **CLAIM**

The ornamental design for a component for a portable display device, as shown and described.

DESCRIPTION

FIG. 1 is a front view of a component for a portable display device showing the claimed design;

FIG. 2 is a rear view thereof;

FIG. 3 is a top view thereof;

FIG. 4 is a bottom view thereof;

FIG. 5 is a side view thereof;

FIG. 6 is another side view thereof; and,

FIG. 7 is an enlarged perspective view of the portion of the component for a portable display device circled with a dot-dash line in FIG. 1.

The dot-dash broken line in FIG. 1 indicates from where the enlarged view in FIG. 7 is taken and forms no part of the claimed design.
